UNITED STATES PATENT OFFICE.

JOHN GRAVES, OF MADISON, WISCONSIN, ASSIGNOR TO FRENCH BATTERY & CARBON COMPANY, OF MADISON, WISCONSIN, A CORPORATION OF WISCONSIN.

EJECTING MECHANISM FOR BATTERY-CORE-MAKING MACHINES.

Original application filed July 5, 1918, Serial No. 243,503. Divided and this application filed March 14, 1921. Serial No. 452,072.

To all whom it may concern:

Be it known that I, JOHN GRAVES, a citizen of the United States, residing at Madison, in the county of Dane and State of Wisconsin, have invented a certain new and useful Improvement in Ejecting Mechanism for Battery-Core-Making Machines, of which the following is a specification.

In the manufacture of what are commonly known in the trade as dry batteries, for use in hand flash lamps and the like, it is common to surround a fixed carbon pencil with a more or less tightly pressed cylinder of depolarizing chemicals, commonly called mix. In practice heretofore it has frequently been common to insert the carbon pencil in the mold and then tamp the depolarizing material or mix about it, but more satisfactory results are obtained both in operative manipulation of manufacture and in actual use in a battery, if the cylinder of depolarizing material is first formed in a mold and then the carbon pencil is pressed into it.

United States patent application, Serial Number 243,503, filed July 5, 1918 of which this application is a division, shows a machine for inserting a carbon pencil in a cylinder of mix and shows, but does not claim, the mechanism of this application for ejecting the finished product from the mold.

The object of this invention is to provide a comparatively cheap, easily constructable and efficiently operating mechanism for removing the finished mix and carbon pencil from the machine. The invention consists in mechanism for attaining the foregoing objects and in many features and details of construction which will be hereafter more fully set forth in the specification and claims.

Figure 1 is a front and Figure 2 a side view of mechanism illustrating this invention in its preferred form.

Figure 3 is a detail view of the ejector plunger showing means for adjusting it for substituting a new tool.

For convenience of ready comparison with the original application from which this application is divided, the same reference numerals used in said original application are retained in this one to designate the various parts.

This part of the mechanism is contained within the general portion 62 of the frame

of the machine, of said prior application. 55 The principal object of the invention is to properly remove the finished product consisting of the cylinder of mix 386 carrying the carbon pencil 384 from the mold 52 sustained by table member 50 fully described 60 in the original application. Broadly speaking the ejector mechanism consists simply of a reciprocating rod 458, carrying at its lower end a detachable tool 460 adjustable as to size by substitution as in the case of 65 tool 454, and adjustable as to length through the agency of screw threads 462; this in combination with means operated by shaft 370 for at the proper time driving this plunger 458 downward into the registering 70 mold to drive out therefrom the finished product 384-386 into a suitable receptacle or chute 466. The problem, however, presented in working with the particular product in hand requires that the rod 458 with 75 attached tool 460 be given a slight rotary motion as it descends through the mold and that, as the product is released from the mold, it be given a sharp stroke or kick to effectively eject it without injuring the conformation of the compressed cylinder of depolarizing material, which is at the time moist and more or less soft. This result is accomplished by mechanism illustrated in 80 Figures 1 and 2. A crosshead 468 is provided, guided for vertical movement in any suitable manner, as for instance, by a pin 470, vertically slid able in a suitable slot 472 formed in frame casting 62. This crosshead 468 is connected for reciprocation by 85 shaft 370 by any suitable means such, for instance, as a wheel 474, mounted on the shaft, and a connecting rod 476, attached at one end to the wheel and at the other end to the crosshead. Instead of making rod 458 integral with this crosshead as would do, if rotation of the rod were not required, the rod 458 is made rotatable in the crosshead, being held against longitudinal movement with reference to the crosshead by a 90 grooved wheel 478, rigidly secured on ejector rod 458 by any suitable means not shown in detail. Pivotally mounted on opposite sides of crosshead 468 and in proper relation to grooved pulley 478, are two other 95 pulleys 480 and 482. Traversing these two pulleys 480 and 482 and the interpersed grooved pulleys 478, is a coiled spring mem- 100 105

ber 484, attached at one end to the upper portion of the frame 62 by any suitable means, such as screw 486, and at its other end to the lower portion of the frame by 5 screw 488. The result of this construction is that, assuming the parts are in the position shown in Figure 1 and the wheel 474 is rotated, the crosshead 468 is moved downward. This causes pulleys 478, 480 and 482 10 to travel along spring 484, but under sufficient frictional engagement so that the pulleys and particularly 478 are rotated, thus slowly rotating member 458—460. As the crosshead descends the frictional engagement 15 of these pulleys with the spring 484 tends to stretch that portion of the spring which is above the pulleys, between them and fastening 486, with the result that when tool 460 has moved through mold 52 sufficiently to eject the product 384—386, this 20 spring is under a severe tension. As the product begins to loosen and leave the mold, this tension of the spring exerts itself to produce a quick pull over the pulleys and 25 thus give tool 460 a quick rotary motion as the finished product leaves the mold, which action in actual practice produces the desired result of a properly finished product member.

30 Having thus described my invention, what I claim as new and desire to secure by Letters Patent, is:

1. In a device of the class described, the 35 combination of a fixed support, a plunger rotatable and reciprocatable with reference thereto, means for rotating said plunger, means for reciprocating said plunger, a spring member in connection with the rotating device adapted to apply spring tension 40 to said plunger as it rotates.

2. In a device of the class described, the 45 combination of a suitable support, a rotatable and reciprocatable member mounted therein, means for reciprocating said member, a retractile spring having its ends fixed and its middle portion passing around the outside of said reciprocating member in such a way that the reciprocation of said 50 member rotates said member and stretches one end of said spring for the purposes set forth.

3. In a device of the class described, the combination of a suitable support, a plunger adapted for reciprocation and rotation with-

in the support, a crosshead guided by the 55 support within which said plunger rotates but does not slide, a pulley carried by the crosshead rigid with the plunger, a belt of spring material connected to the crosshead and passing around said pulley on the 60 plunger, means for reciprocating the crosshead whereby reciprocating the crosshead causes the plunger to reciprocate and the pulley to pass along the spring, thus rotating the plunger and putting it under tension, for the purposes set forth. 65

4. In a device of the class described, the combination of a suitable support, having parallel arms projecting therefrom, a retractile spring member having its opposite 70 ends connected to said arms, a crosshead mounted for movement between said arms, a main pulley having its axles parallel to the general length of the spring member, two guiding pulleys at right angles thereto, all 75 mounted on the crosshead in such a way that the spring member passes over said main pulley, a plunger member slidale and rotatable with reference to the support, mounted rotatably in the crosshead to be driven by 80 the main pulley and means for reciprocating the crosshead between said projecting arms of the frame for the purposes set forth.

5. In a device of the class described, the combination of a supporting frame, a rotatable and reciprocatable ejecting member, a 85 crosshead reciprocatable with reference to the frame, a pulley in the crosshead to which the ejector member is rigidly attached but with which it rotates, a retractile spring 90 member connected at its ends to fixed parts in the frame and passing over said pulley for the purpose of giving the ejector member a spring tension rotary movement, a shaft at right angles to the ejector member, a connecting rod attached to said crosshead and operatably connected with the shaft, whereby rotating of the shaft reciprocates the ejector member, and rotates it under increasing spring tension, as and for the purposes set forth. 95

In witness whereof, I have hereunto subscribed my name in the presence of two witnesses.

JOHN GRAVES.
